WILLIAM A. SMITH, JR., OF PHILLIPSBURG, NEW JERSEY, ASSIGNOR TO INGERSOLL-RAND COMPANY, OF JERSEY CITY, NEW JERSEY, A CORPORATION OF NEW JERSEY

BLOWING DEVICE FOR ROCK DRILLS

Application filed December 14, 1928. Serial No. 325,986.

This invention relates to rock drills, but more particularly to a blowing device for fluid actuated rock drills of the hammer type.

One object of the invention is to selectively admit an uninterrupted flow of pressure fluid through the rock drill and the drill steel into the drill hole for blowing the cuttings therefrom.

Another object is to maintain the distributing valve firmly seated in the valve chamber during the blowing operation unaffected by any pressure fluid which may exert a force thereon tending to unseat the valve during the blowing operation.

Other objects will be in part obvious and in part pointed out hereinafter.

In the drawings illustrating the invention and in which similar reference characters refer to similar parts,

Figure 1 is a sectional elevation of a portion of a rock drill having the invention applied thereto,

Figure 2 is a transverse view taken through Figure 1 on the line 2—2 looking in the direction indicated by the arrows, and

Figure 3 is a view similar to Figure 1 showing a modified form of the invention.

Referring to the drawings, A represents a cylinder of a rock drill having a piston chamber B in which is disposed a reciprocating hammer piston C for delivering blows of impact to a working implement (not shown).

The piston C carries at its front end an extension D which extends slidably through a bore

E of a front cylinder washer F disposed in the front end of the cylinder A to form a closure therefor. The extension D is provided with the usual flutes G to slidably interlock with chuck mechanism (not shown) in a well known manner for rotating the working implement.

The cylinder A has an exhaust port H which is normally controlled by the piston C, and in the rearward end of the cylinder A is an enlarged bore J to receive a back cylinder washer K which forms a closure for the rearward end of the piston chamber B. The back cylinder washer K serves as a seat for a rotation ratchet L in the rearward end of the bore J and serving as a seat for a back

head O at the rearward end of the cylinder A.

The rotation ratchet L has introverted teeth P to act as abutments for spring pressed pawls Q carried by the head R of a rifle bar S to impart a step by step rotary motion to the piston C wherewith the rifle bar S is slidably interlocked.

The admission of pressure fluid into the drill is controlled by a throttle valve T seated in the back head O and having a lever U whereby the throttle valve T may be rotated. The pressure fluid may be conveyed to the drill by a suitable conduit (not shown) from a source of supply and is intended to be admitted into a central chamber V of the throttle valve T wherewith it may be in constant communication. In the side of the throttle valve T is a port W which, in the open position of the throttle valve T, registers with a passage X leading to a supply reservoir Y in the forward end of the back head O.

From the supply reservoir Y the pressure fluid flows through supply passages Z in the rotation ratchet L into a valve chamber b, in this instance of annular form, and formed in the front end of the rotation ratchet L.

The valve chamber b communicates with the front and rearward ends of the piston chamber B through inlet passages c and d respectively. The inlet passage d opens directly into the rearward end of the piston chamber B and the inlet passage c is formed in the back cylinder washer K and in the wall of the cylinder A and opens into the front end of the piston chamber.

The means whereby the distribution of pressure fluid to the ends of the piston chamber B is effected consists in this instance of an oscillatory plate type valve e in the form of a ring and having a fulcrum f on its transverse median line whereon said valve is adapted to rock from one limiting position to another. The valve e thus has wings g and h on opposite sides of the fulcrum f which controls the inlet passages d and c respectively.

During the normal operation of the parts of the drill so far described the flutes G of the piston extension D will be drawn into the forward end of the piston chamber B

upon each rearward stroke of the piston and a portion of the pressure fluid utilized for actuating the piston C rearwardly will flow through said flutes and through the forward 5 part of the drill into the working implement and into the drill hole for removing the cuttings therefrom.

Under certain conditions the amount of fluid admitted into the drill hole in this manner may suffice to maintain the drill hole 10 fairly clean. There are conditions, however, where this method of cleansing the drill hole has been found inadequate as the cuttings accumulate more rapidly than they can be removed from the drill hole. When this occurs 15 the dust and broken rock particles will be moved rearwardly of the cutting bit around which they form a collar and, due to the increased friction on the rock greatly interfere 20 with the action of the drill.

It is desirable that the cuttings in most drilling operations should be removed as rapidly as they are formed and to this end means are provided in the present instance to effect 25 a thorough cleansing of the drill hole whenever the ordinary means provided for this purpose are found to be inadequate. Accordingly the cylinder A is provided with a throttle valve chamber j which extends transversely through the exhaust port H for the 30 reception of a blower valve k, shown in this instance as being of the rotatable type and having a lever o whereby it may be rotated from the open to the closed position, and vice 35 versa.

In one side of the blower valve k is a recess p which, in the open position of the blower valve, will permit the free escape of pressure fluid through the exhaust port H during the 40 normal operation of the drill.

By using the flutes G in the piston extension D as channels for conveying the pressure fluid from the piston chamber to the working implement pressure fluid should enter only 45 the front end of the piston chamber, and to accomplish this result the valve e should of course remain immovable in the valve chamber so that pressure fluid may flow only over one end thereof, in this instance over the 50 end h.

Ordinarily during blowing and when distributing valves of the type illustrated are used there is some tendency for the pressure fluid flowing over the raised end of the valve 55 to exert a force thereon tending to raise the opposite or seated end of the valve. This admits pressure fluid in small quantities into the rearward end of the piston chamber and tends to move the piston C into a position 60 in which the flutes G will lie entirely within the bore E of the front cylinder washer, thus cutting off the supply of pressure fluid to the working implement. Means are accordingly provided to assure the retention of the distributing valve e in the position which it

should occupy during the blowing operation. To this end a passage q is formed in the back cylinder washer K and in the cylinder A to open with one end into a cavity r in the back cylinder washer K at a point near the inlet 70 passage d and directly beneath the wing g of the valve e so that when the end g of the valve e is seated on the back cylinder washer K the cavity r will be completely covered by the valve. 75

The opposite end of the passage q opens into the throttle valve chamber j and registers with a port s in the blower valve k in the closed position of the blower valve. The port s extends through the blower valve k 80 and opens into the outlet opening of the exhaust port H. In this way when the blower valve k is closed the cavity r will be in direct communication with the atmosphere. 85

In order to create a vacuum in the cavity r while blowing is taking place the back cylinder washer K is provided with a port t which has its inlet opening outside of the edge of the valve e and opens with its other end into the passage q so that when the blower valve k is closed pressure fluid may flow from the valve chamber b through the port t into the passage q and create a sub-atmospheric pressure in the cavity r which will tend to maintain the end g of the valve firmly seated on the back cylinder washer K. 90

The operation of the device is as follows: Let it be assumed that the drill is operating in the normal manner, that is, the piston C is delivering its blow against the working implement. If then, the cuttings in the drill hole accumulate to an extent which will render the ordinary blowing means for removing the cuttings ineffective, the blower valve k may be closed to prevent the escape of fluid 105 from the piston chamber.

In the closed position of the blower valve k the passage q will be open to the atmosphere through the port s in the blower valve and the valve end g will then seat on the back cylinder washer K so that the pressure fluid may flow over the end h of the valve e through the inlet passage e into the front end of the piston chamber to move the piston C rearwardly a sufficient distance to hold the flutes G in communication with the front end of the piston chamber. Pressure fluid will then escape through the flutes and through the front part of the drill into the drill steel and into the drill hole and will blow the cuttings therefrom. 110

During the blowing of the drill hole pressure fluid will be constantly flowing from the valve chamber d through the port t into the passage q and will create a vacuum in the cavity r which will assist in maintaining the end g of the valve firmly seated on the back cylinder washer K. This will stabilize the valve e during the blowing operation. After the hole has been cleansed the blower valve k 115

may be rotated to the open position and normal drilling will then again be resumed.

In the open position of the throttle valve the recess *p* will establish communication between the piston chamber *B* and the exhaust port *H*, and the outlet opening of the passage *q* will be closed by the blower valve *k* so that the distributing valve *e* may then operate in a normal manner for distributing the pressure fluid to the ends of the piston chamber *B*.

The modified form of the invention illustrated in Figure 3 is in most respects like that described in connection with the preferred modification. In this instance the drill is also provided with a passage *q* which leads from the cavity *r* to the exhaust port *H* and a port *u* is formed in the wing *g* of the valve *e* to introduce pressure fluid into the passage *q* for creating the sub-atmospheric pressure therein to hold the end *g* of the valve firmly seated during the blowing operation.

I claim:

1. In a fluid actuated rock drill, the combination of a cylinder and a piston having a fluted extension, an exhaust port in the cylinder, a valve chamber, inlet passages leading from the valve chamber to the cylinder, a distributing valve in the valve chamber controlling the inlet passages, a blower valve for closing the exhaust port to arrest the movement of the distributing valve thus causing pressure fluid to flow through only one inlet passage into the cylinder and through the flutes in the piston extension, a passage leading from the valve chamber to the exhaust port and controlled by the valve, and a port injecting pressure fluid from the valve chamber through the passage to create a vacuum in a portion of the valve chamber tending to maintain the distributing valve firmly seated during the blowing operation.

2. In a fluid actuated rock drill, the combination of a cylinder and a piston, a fluted extension on the piston, an exhaust port in the cylinder, a valve chamber, inlet passages leading from the valve chamber to the cylinder, an oscillatory plate valve having a pair of wings to control the inlet passages, a passage leading from one end of the valve chamber to the exhaust port, a blower valve for closing the exhaust port to arrest the movement of the plate valve thus causing pressure fluid to flow through an inlet passage into one end of the cylinder and through the flutes in the extension, and a port for conveying pressure fluid from the valve chamber into the passage to create a vacuum beneath the seated end of the plate valve to hold said plate valve firmly seated during the blowing operation.

3. In a fluid actuated rock drill, the combination of a cylinder and a piston, a fluted extension on the piston, an exhaust port in the cylinder normally controlled by the piston, a valve chamber, inlet passages leading from the valve chamber to the cylinder, an oscillatory plate distributing valve having a pair of wings to control the inlet passages, a passage opening at one end into the exhaust port and with its other end in the valve chamber beneath one wing of the valve, a blower valve for closing the exhaust port to arrest the movement of the distributing valve thus causing pressure fluid to flow through only one inlet passage into the cylinder and through the flutes in the extension, and a port for conveying pressure fluid from the valve chamber into the passage for creating a vacuum beneath the seated end of the valve to hold said valve firmly seated during the blowing operation.

4. In a fluid actuated rock drill, the combination of a cylinder and a piston, a fluted extension on the piston, an exhaust port in the cylinder normally controlled by the piston, a valve chamber, inlet passages leading from the valve chamber to the cylinder, an oscillatory plate distributing valve having a pair of wings to control the inlet passages, a passage opening at one end into the exhaust port and with its other end in the valve chamber beneath one wing of the valve, a blower valve for closing the exhaust port to arrest the movement of the distributing valve thus causing pressure fluid to flow through only one inlet passage into the cylinder and through the flutes in the extension, and a port for conveying pressure fluid from the valve chamber into the passage for creating a vacuum beneath the seated end of the valve to hold said valve firmly seated during the blowing operation.

5. In a fluid actuated rock drill, the combination of a cylinder and a piston, a fluted extension on the piston, an exhaust port in the cylinder, a valve chamber, inlet passages leading from the valve chamber to the cylinder, a distributing valve in the valve chamber controlling the inlet passages, a blower valve for closing the exhaust port to arrest the movement of the distributing valve thus causing pressure fluid to blow through one inlet passage into the front end of the cylinder and through the flutes in the extension, a port for conveying pressure fluid from the valve chamber into the passage for creating a vacuum beneath the seated end of the distributing valve to hold said valve firmly seated during the blowing operation, and a port in the blower valve affording communication between the passage and the atmosphere in the closed position of the blower valve.

In testimony whereof I have signed this specification.
